CLAIM

The ornamental design for an animal food and treat dispenser, as shown and described.

DESCRIPTION

FIG. 1 is a perspective of the animal food and treat dispenser in a first embodiment;

FIG. 2 is a front elevation view of the animal food and treat dispenser of FIG. 1;

FIG. 3 is a rear elevation view of the animal food and treat dispenser of FIG. 1;

FIG. 4 is a right side view of the animal food and treat dispenser of FIG. 1;

FIG. 5 is a left side view of the animal food and treat dispenser of FIG. 1;

FIG. 6 is a top plan view of the animal food and treat dispenser of FIG. 1;

FIG. 7 is a bottom plan view of the animal food and treat dispenser of FIG. 1;

FIG. 8 is a perspective of the animal food and treat dispenser in a second embodiment;

FIG. 9 is a front elevation view of the animal food and treat dispenser of FIG. 8;

FIG. 10 is a rear elevation view of the animal food and treat dispenser of FIG. 8;

FIG. 11 is a right side view of the animal food and treat dispenser of FIG. 8;

FIG. 12 is a left side view of the animal food and treat dispenser of FIG. 8;

FIG. 13 is a top plan view of the animal food and treat dispenser of FIG. 8; and,

FIG. 14 is a bottom plan view of the animal food and treat dispenser of FIG. 8.
